(57) **CLAIM**

The ornamental design for electrical service socket adapter housing, as shown and described.

DESCRIPTION

FIG. 1 is a bottom view of a first embodiment of an electrical service socket adapter housing showing the new design;

FIG. 2 is a perspective view thereof;

FIG. 3 is a front view thereof;

FIG. 4 is a back view thereof;

FIG. 5 is a top view thereof;

FIG. 6 is a right side view thereof, the left side view being a mirror image thereto;

FIG. 7 is a perspective view of a second embodiment of an electrical service socket adapter housing showing the new design;

FIG. 8 is a front view thereof;

The bottom, back, top and sides views of the second embodiment are the same as FIGS. 1, 4, 5 and 6 respectively;

FIG. 9 is a perspective view of a third embodiment of an electrical service socket adapter housing showing the new design;

The bottom, front, back, top and sides views of the third embodiment are the same as FIGS. 1, 8, 4, 5 and 6 respectively; and,

FIG. 10 is a perspective view of a fourth embodiment of an electrical service socket adapter housing showing the new design.

The bottom, front, back, top and sides views of the fourth embodiment are the same as FIGS. 1, 8, 4, 5 and 6 respectively.

The broken line portion of the figure drawings is included to show unclaimed subject matter only and forms no part of the claimed design.
